UNITED STATES PATENT OFFICE.

ANDREW P. JAMES, OF SHERMAN, TEXAS.

DEVICE FOR HANDLING SEED-COTTON TO BE GINNED.

SPECIFICATION forming part of Letters Patent No. 240,722, dated April 26, 1881.

Application filed March 1, 1881. (No model.)

To all whom it may concern:

Be it known that I, ANDREW P. JAMES, a citizen of the United States, residing at Sherman, in the county of Grayson and State of Texas, have invented new and useful Devices 5 for Handling Seed-Cotton to be Ginned, of which the following is a specification.

My invention relates to improvements in devices for handling seed-cotton to be ginned, 10 in which a track is laid and box-cars suitable for storing cotton employed in place of bins in the gin-house, as heretofore; and the objects of my invention are, first, to provide a convenient method of handling the cotton; 15 second, to afford facilities for the safe storing of the same at a distance from the engine and gin-building; and, third, to reduce the cost of the gin-building and danger of fire by storing the cotton in cars along the track at a distance 20 from the gin-house. I attain these objects by the devices illustrated in the accompanying drawings, in which—

Figure 1 is a vertical end elevation of the gin-building, showing a side view of the track; 25 Fig. 2, a side view of the building, showing end view of tramway; Fig. 3, a section on the line *x x*, Fig. 1, showing the second floor of the building; and Fig. 4, a section through the line *1 2*, Fig. 1, showing first floor of the 30 building.

Similar letters refer to similar parts throughout the several views.

The sills A, posts B, and cross-timbers C constitute the frame-work of the building, 35 which should be set at the side of a bank, bringing the second floor D level with the surface. Upon this floor, and extending back about one hundred yards along the bank, I lay a double tramway, E, of wood, and provide 40 a simple switch, F, at each end, for transferring the cars from one track to the other.

G represents the style of car I deem preferable for storing the cotton, and as many may be employed as the business requires. They 45 should be ten feet long, three feet eight inches wide at bottom, four feet eight inches wide at top, and the sides three feet high. The roof should have one foot pitch from center of car each way, and made tight to shed rain. One 50 side of roof is nailed down, the other hinged to it at center, forming a lid, which may be

opened and swung back for the reception of cotton from wagons bringing it to the gin, and as many wagons may unload at a time as there are empty cars on the track without waiting 55 for each other to unload, as heretofore. The side of car nearest to gin-stand H has a door extending from top to bottom of side, which, when a car is run into the building to be emptied, is taken out and the cotton removed 60 through it and placed in the gin. Each car should be provided with a lock, and have its weight and number marked upon it in a conspicuous place.

The switch-rails F of tramway rest upon 65 platform-scales J, which should be placed opposite gin-stand H. With this arrangement a whole car of cotton, when run in to be ginned, may be weighed at once, instead of by baskets, as heretofore. When a car is unloaded it is 70 switched off on the side track and run back out of the building to be filled again.

K represents an open-top car constructed so as to dump on either side. This car runs upon a single straight track, L, passing directly under the gin on lower floor of building. The seed, as it falls from the gin, drops 75 into this car, which should be emptied at one of the numbered posts M, stationed at convenient distances apart outside of the building, as often as any one customer's cotton is 80 ginned.

I am aware that prior to my invention cars and tramways have been constructed similar to mine and employed for various purposes; 85 but I am not aware that they have been used in conjunction with a gin-building to facilitate the handling of seed-cotton.

What I therefore claim as new, and desire to secure by Letters Patent, is—

1. The combination, with a gin-house constructed as shown, of the double tramway E and cars G, provided with switch F, resting upon scales J, substantially as set forth.

2. The track L, seed-car K, and numbered 95 posts M, in combination with a gin-house, for the purposes herein specified.

ANDREW P. JAMES.
